CLAIM

The ornamental design for a display screen or portion thereof with animated graphical user interface, as shown and described.

DESCRIPTION

FIG. 1 and FIG. 2 are the first and second images, respectively, in a sequence for a display screen or portion thereof with animated graphical user interface showing our new design; and,

In another embodiment, FIG. 3 and FIG. 4 are the first and second images, respectively, in a sequence for a display screen or portion thereof with animated graphical user interface showing our new design.

The outermost broken lines shown in the figures illustrate a display screen or portion thereof and form no part of the claimed design.

The appearance of the animated graphical user interface sequentially transitions between the images shown in FIG. 1 and FIG. 2. The process or period in which one image transforms to another forms no part of the claimed design. In another embodiment, the appearance of the animated graphical user interface sequentially transitions between the images shown in FIG. 3 and FIG. 4. The process or period in which one image transforms to another forms no part of the claimed design.
